(57) **CLAIM**

I claim the ornamental designs for a watch clasp, as shown and described.

DESCRIPTION

FIG. 1 is a perspective view of a watch clasp in an open position;

FIG. 2 is a perspective view of the watch clasp in a closed position;

FIG. 3 is a top plan view of the watch clasp in the open position of FIG. 1;

FIG. 4 is a top plan view of the watch clasp in the closed position of FIG. 2;

FIG. 5 is a bottom plan view of the watch clasp in the open position of FIG. 1;

FIG. 6 is a bottom plan view of the watch clasp in the closed position of FIG. 2;

FIG. 7 is a right side elevation view of the watch clasp in the open position of FIG. 1;

FIG. 8 is a right side elevation view of the watch clasp in the closed position of FIG. 2;

FIG. 9 is a left side elevation view of the watch clasp in the open position of FIG. 1;

FIG. 10 is a left side elevation view of the watch clasp in the closed position of FIG. 2;

FIG. 11 is a front elevation view of the watch clasp in an open position of FIG. 1;

FIG. 12 is a front elevation view of the watch clasp in the closed position of FIG. 2;

FIG. 13 is a back elevation view of the watch clasp in the open position of FIG. 1; and,

FIG. 14 is a back elevation view of the watch clasp in the closed position of FIG. 2.

The broken lines in the drawings are for descriptive purposes only and form no part of the claimed design.
